Primary Examiner — Lauren R Calve*(74) Attorney, Agent, or Firm* — Sandberg Phoenix & von Gontard, P.C.(57) **CLAIM**

The ornamental design for an adjustment knob assembly, as shown and described.

DESCRIPTION

FIG. 1 is a top perspective view of an adjustment knob assembly;

FIG. 2 is a front view of the adjustment knob assembly;

FIG. 3 is a rear view of the adjustment knob assembly;

FIG. 4 is a right side view of the adjustment knob assembly;

FIG. 5 is a left side view of the adjustment knob assembly;

FIG. 6 is top plan view of the adjustment knob assembly; and,

FIG. 8 is a perspective view of the adjustment knob assembly shown in environmental use installed on a wheel balancer system.

The broken lines shown within the drawings illustrate features that form no part of the claimed design.
